(57) **CLAIM**

The ornamental design for a vehicle locating device, as
shown and described.

DESCRIPTION

FIG. 1 is an environmental perspective view of a vehicle
locating device showing my new design;

FIG. 2 is a front elevational view, with the rear being a
mirror image, thereof;

FIG. 3 is a left side elevational view thereof;

FIG. 4 is right side elevational view thereof;

FIG. 5 is a top view thereof; and,

FIG. 6 is a bottom view thereof.

The broken line showing of the automobile in FIG. 1 is for
illustrative purposes only and forms no part of the claimed
design.

1 Claim, 5 Drawing Sheets
